METALLIC CONTAINER

Wallace C. Mills, Rockford, Ill., assignor to J. L. Clark Manufacturing Co., Rockford, Ill., a corporation of Illinois

Application April 5, 1937, Serial No. 135,004

3 Claims. (Cl. 220—10)

The invention relates to small jars of the type commonly employed as containers for cold cream, ointments, and the like. Such containers have heretofore been made of glass. More recently, it has been proposed to construct such containers of sheet metal as, for example, by utilizing cooperating inner and outer sheet metal shells as shown in Patent No. 2,044,093, issued June 16, 1936. Such sheet metal containers reduce the weight and fragility of the article as compared to a glass container. There are also other advantages resulting from the use of sheet metal in fabricating the container, such as its greater adaptability for decoration.

One object of the present invention is to provide a container of the type set forth including inner and outer shells and embodying an improved arrangement for maintaining such shells in assembled relation to form a rugged, economically manufactured container of pleasing appearance.

Another object of the present invention is to provide an improved container of the type set forth having its several component parts formed from sheet metal and so fashioned that they may be quickly and easily assembled to form a strong finished structure.

Further objects and advantages of the invention will become apparent as the following description proceeds and the features of novelty which characterize the invention are pointed out with particularity in the claims annexed to and forming a part of this specification.

For a better understanding of the invention, reference may be had to the accompanying drawings in which

Figure 1 is a perspective view of a container embodying the invention.

Fig. 2 is an enlarged vertical transverse sectional view along the line 2—2 in Fig. 1.

Fig. 3 is an enlarged perspective detail view of the bottom closure member included in the container shown in Figs. 1 and 2.

For purposes of illustration, the invention has been shown as embodied in a jar or container particularly adapted for cold cream or similar viscous cosmetics and the like. A double walled construction for the container is had by utilizing inner and outer sheet metal shells preferably so fashioned that the interior of the container will have an entirely smooth surface terminating in a broad rounded edge at the top of the container. An improved arrangement is had for retaining the inner and outer shells in their assembled relation. The particular container illustrat-

ed comprises inner and outer shells designated generally by the numerals 10 and 11, respectively.

The inner shell 10 is preferably cup-shaped and may be formed from a single sheet of metal drawn to provide a bottom wall 12 and a side wall 13 terminating in a comparatively wide outwardly flaring lip 14 extending entirely about the upper edge of the inner shell. A smooth interior surface entirely free from joints or crevices is thus had as the lip 14 forms a smooth continuation of the inner side walls of the container so that there is no crevice nor irregularity in which the contents of the jar may become lodged. In the preferred construction illustrated, the lip 14 also includes a downwardly projecting portion 15 arranged in spaced relation with respect to the adjacent upper end of the side wall of the shell and adapted to receive the adjacent edge of the outer shell 11.

The exterior side walls of the container are formed by the generally tubular outer shell 11 which in the preferred construction illustrated, is provided with successive shoulders 16 and 17 at its upper end. Upon reference to Fig. 2, it will be seen that the upper portion of the outer shell 11 is press fitted within the portion 15 of the inner shell, frictionally engaging the same. A suitable closure cap may be fitted over the top of the container with its lower edge resting against the shoulder 16 on the outer shell. The shouldered upper portion of the outer shell 11 is given a smooth contour, as illustrated, in the event that a suction cap is to be utilized and may be formed with lugs or projections thereon if it is desired to use a threaded cap.

In accordance with the present invention, an improved arrangement has been provided for maintaining the lower end portion of the inner shell 10 in spaced relation to the side walls of the outer shell 11. To this end, a resilient sheet metal cup designated generally by the numeral 18 is fitted in the lower end of the outer shell 11 and is disposed in frictional engagement with the lower end portion of the inner shell 10. This cup 18 includes a flat bottom wall 19 on which the bottom wall 12 of the inner shell 10 rests, and an annular side wall 20. The entire upper portion 21 of the cup side wall 19 is bent inwardly and resiliently engages the adjacent side walls of the inner shell 10 at spaced points only, this engagement and bending of the cup side wall being had by crimping or folding the same at spaced points as indicated at 22. The cup 18 is preferably positioned in the outer shell 11 by press fitting the same within an open inwardly

extending annular bead 23 formed on the lower edge of the outer shell.

In assembling the container described above, the inner shell 10 may first be inserted in the outer shell 11 and frictionally secured thereto at its upper end by forcing the edge 15 of the outwardly flaring lip 14 over the adjacent portion of the outer shell and into abutment with the shoulder 17. The sheet metal cup 18 is then inserted in the lower end of the outer shell 11, being press fitted therein, and indentations or folds 22 in the side wall of the cup grip the adjacent side walls of the inner shell 10 tightly due to the resilient character of the material from which they are formed. The parts of the container are thus snugly fitted together in a strong rigid structure. It will also be noted that the bottom wall 19 of the cup 18 forms a smooth bottom for the container thereby giving it a pleasing appearance and also closes the lower ends of the air spaces between the spaced side walls of the shells.

Although a particular embodiment of the invention has been shown and described in some detail for purposes of illustration, there is no intention to thereby limit the invention to such embodiment but on the other hand, the appended claims are intended to cover all modifications within the spirit and scope of the invention.

I claim as my invention:

- 30 1. A container of the type set forth comprising, a tubular outer shell, a cup-shaped inner shell

disposed within said outer shell in spaced relation thereto, an outwardly flaring lip formed on said inner shell and overlying the upper edge of said outer shell, said upper edge of said outer shell being frictionally telescoped within said lip 5 and a sheet metal cup press fitted in the lower end of said outer shell and having spaced portions of the side walls thereof bent inwardly into frictional engagement with the lower end portion of said inner shell for maintaining the same in 10 predetermined spaced relation with respect to the side walls of said outer shell.

2. A container of the type set forth comprising, a tubular outer shell, a cup-shaped inner shell disposed within said outer shell, said inner and 15 outer shells being secured together at their upper ends and the side walls thereof being located in spaced relation, said outer shell having an inwardly extending annular bead formed on the lower edge thereof, and a closure for the bottom of the container embodying a sheet metal cup telescoped within the lower end of said outer shell and press-fitted against said bead, the upper edge of the side wall of said cup being crimped inwardly at spaced points in resilient engagement with the side walls of the lower portion of said inner shell for maintaining the same in predetermined spaced relation with respect to the side walls of said outer shell.
